UNITED STATES PATENT OFFICE.

JOAQUIN GARCIA DE QUESADA, OF BARCELONA, SPAIN.

REFRIGERATING APPARATUS.

1,025,765.

Specification of Letters Patent. Patented May 7, 1912.

Application filed August 28, 1911. Serial No. 646,313.

To all whom it may concern:

Be it known that I, JOAQUIN GARCIA DE QUESADA, manufacturer, a subject of the King of Spain, residing at Barcelona, in the Province of Barcelona and Kingdom of Spain, have invented certain new and useful Improvements in Refrigerating Apparatus; and I do hereby declare the following to be a full, clear, and exact description 5 of the invention, such as will enable others skilled in the art to which it appertains to make and use the same.

My invention relates to an improved refrigerating apparatus, and it consists in the 10 constructions, combinations and arrangements herein described and claimed.

An object of my invention is to provide a simple and compact refrigerating apparatus comprising a portable generator having 15 a source of gas under pressure and an absorbent for such gas, adapted to be detachably secured to any suitable cooling coil and to constitute with said coil a closed system for the expansion, circulation and 20 condensation or absorption of a gas; thereby providing a convenient and economical apparatus for domestic use, in which expended generators can be readily detached from the cooling coil and replaced by charged generators, and the gas recovered from the absorbents of expended generators and compressed for recharging the same.

In the accompanying drawings forming a part of this application, and in which 25 similar reference symbols indicate corresponding parts in the several views:—Figure 1 is a sectional view on the line I—I of Fig. 2, illustrating one embodiment of my invention; and, Fig. 2 is a section on the line II—II of Fig. 1.

Referring to the drawings, 3 indicates a 30 perforated casing having a cover 4 secured thereto by bolts 5.

A container, or tank, 8 for strongly compressed or liquefied gas is provided with an 35 outlet valve having a hand wheel 9 in position for convenient operation through an opening in the casing 3 provided with a pivoted cover plate 7. An outlet pipe 10, from said container, is provided with a 40 regulating valve 11, and is adapted to be detachably connected by a union 12 to the valved inlet 22 of any suitable cooling coil 24.

50 A closed receptacle is divided by a horizontal partition 15 into a lower compart-

ment 13 for containing a suitable absorbent for the gas and an upper overflow compartment 17 communicating therewith through an aperture 14 in said partition for permitting expansion of such absorbent during 60 operation; said overflow compartment being provided with a relief valve 19, and with a gage 18 positioned for convenient reading within a window 6 in the casing 3. 65

Any suitable gas and absorbent may be employed, and I have found ammoniacal gas and water to prove entirely satisfactory.

As water is absorbing ammonia increases in volume in proportion to the amount of 70 gas absorbed, the amount of ammonia drawn from the receptacle 8 can be determined by reading the water level in the sight gage 18. This arrangement of the receiver 13 and tank 17 provides an advantageous construction for preventing violent 75 shifting of the contained water during handling and use.

A pipe 16, provided with a valve 20, is detachably connected by a union 21 with the 80 valved outlet pipe 23 of the coil, and extends through the overflow compartment 17 to the lower portion of the lower compartment. Suitable braces 28 and 29 are shown for supporting the container and receptacle 85 in the casing 3.

In the operation of my invention, the gas under pressure is admitted to the pipe 10 by turning the hand wheel 9, and the valve 11 adjusted to regulate the expansion of 90 such gas supply in the coil 24; thereby regulating the rate of supply and degree of expansion within said coil. After cooling the coil by circulating therethrough, the gas is discharged into the lower compartment 13, 95 where it is absorbed by the absorbent material therein; thereby maintaining a reduced pressure on the discharge end of said coil for insuring an efficient circulation there- 100

From the above description, it will be clear that my invention provides a simple and compact refrigerating apparatus comprising a portable generator having a source of gas under pressure and an absorbent for 105 such gas, adapted to be detachably secured to any suitable cooling coil and to constitute with said coil a closed system for the expansion, circulation and condensation or absorption of a gas; thereby providing a 110 convenient and economical apparatus for domestic use, in which expended generators

can be readily detached from the cooling coil and replaced by charged generators, and the gas recovered from the absorbers of expanded generators and compressed for re-charging the same.

I claim:—

1. In a refrigerating apparatus provided with a cooling coil, the combination of a portable generator comprising a container for gas under pressure and a closed receptacle divided by an apertured partition into a lower compartment for normally containing an absorbent of such gas and a communicating upper overflow compartment, a valved pipe communicating with the lower portion of said lower compartment, a valved pipe leading from said container, and means for detachably securing said container pipe and lower compartment pipe respectively to the inlet and outlet of the coil.
- 10 15 20

2. In a refrigerating apparatus provided with a cooling coil, the combination of a portable generator comprising a container for gas under pressure and a closed receptacle divided by an apertured partition into a lower compartment for normally containing an absorbent of such gas and a communicating upper overflow compartment, a valved pipe communicating with the lower portion of said lower compartment, a valved pipe leading from said container, means for detachably securing said container pipe and lower compartment pipe respectively to the inlet and outlet of the coil, and valves in 30 35 said inlet and outlet.

In testimony whereof, I affix my signature, in presence of two witnesses.

JOAQUIN GARCIA DE QUESADA.
